Inventor

J. P. O. L. S. O. M.

Loey, Loey, Attorney

UNITED STATES PATENT OFFICE.

JAMES P. OLSON, OF SANFORD, FLORIDA.

CISTERN CUT-OFF.

Application filed May 6, 1925. Serial No. 28,451.

To all whom it may concern:

Be it known that I, JAMES P. OLSON, a citizen of the United States, residing at Sanford, in the county of Seminole and 5 State of Florida, have invented certain new and useful Improvements in Cistern Cut-Offs, of which the following is a specification.

This invention relates to devices for directing rain water into a cistern and has 10 for its object the provision of means whereby the water flowing from a roof will be diverted to one side until trash and dirt have been eliminated and will then be automatically directed into the cistern. The invention also has for its object the provision of means for the stated purpose which will automatically restore the cut-off device to 15 its initial position after the cistern has been filled. Other objects of the invention will appear incidentally in the course of the following description, and the invention resides in certain novel features which will be particularly pointed out in the appended 20 claims.

In the accompanying drawing:

Figure 1 is an elevation of my improved cut-off device;

Fig. 2 is an enlarged longitudinal ver- 30 tical section, and

Fig. 3 is a transverse vertical section on the line 3—3 of Fig. 2.

In carrying out my invention, I employ a casing 1 which is substantially elliptical 35 in plan view and is provided at its ends with depending outlets 2 and 3. The outlet 2 is a discharge outlet which will permit the water to flow onto the ground and will also permit the escape of sand and 40 like foreign matter which may be carried with the water. The outlet 3 is intended to be coupled by a pipe 4 or the like with a storage cistern. Between the outlets 2 and 3, a float chamber 5 depends from the 45 main casing and is in communication therewith, as clearly shown in Figs. 2 and 3. Pivotally mounted within the casing 1 centrally above the float chamber is a valve or cut-off plate 6 which will direct the 50 water into the outlet 2 or the outlet 3 according to the direction in which it is tilted. The pivot rod 7 which carries the cut-off is provided at one end externally with a crank handle 8 and pivotally mounted upon 55 the casing above the said crank handle is

a latch 9 adapted to engage the free end of the handle so that, when the cistern is full, the device may be set so as to turn all the water into the outlet 2 and prevent further flow into the cistern. This device 60 will be utilized in seasons of excessive rain and will be found efficient to prevent over-flowing of the cistern. In seasons of scanty rain or only normal flows, the latch 9 will be maintained out of engagement with the 65 handle 8, as will be understood.

The valve or cut-off plate 6 is provided centrally with a small opening 10 there-through and within the float chamber 5 is a float 11 which is preferably a hollow 70 ball but may be of any preferred construction, this float being connected with one end of the cut-off plate by a stem 12, as clearly shown in Figs. 2 and 3. The bottom of the float chamber is closed by a 75 removable cap 13, having a small vent opening 14 through its center, so that, if needed, access may be had to the float chamber for cleaning or repairing any of the parts.

Secured within the casing 1 at the ends 80 thereof are inwardly projecting deflectors 15 which are of dished formation and extend slightly downwardly so that their lower free ends are within the paths of the respective ends of the valve. Across 85 the upper end of the casing is secured a screen 16 whereby leaves, sticks and other solid matter which may be washed from the roof will be prevented from passing into the casing with the water. The casing is 90 connected with the down spout 17 by hangers or side plates 18 secured at their lower ends to the side of the casing and at their upper ends to the down spout, as clearly 95 shown. This arrangement leaves an open space between the end of the spout and the screen 16 through which any leaves, trash or other matter which may collect upon the screen may be easily removed.

The weight of the float obviously will 100 overbalance the valve so that it will normally assume the position shown in full lines in Fig. 2 resting at its lower end upon the edge of the outlet 2 at the upper end thereof and resting at its upper end against 105 the under side of the deflector 15 which is over the outlet 3. When water flows through the down spout 17, it will, of course, pass through the screen 16 and will be directed by the deflectors 15 onto the valve or 110

cut-off plate 6, flowing down the same into and through the outlet 2. Some of the water, however, will pass through the opening 10 into the float chamber and, as it will 5 accumulate in said chamber, the float 11 will gradually be raised and eventually will effect a complete tilting of the valve so that it will assume the position shown in dotted lines in Fig. 2 and will direct the water into 10 the cistern. Ordinarily, the flow of water through the opening 10 will be so gradual that all dirt will be eliminated before the valve or cut-off plate is reversed and, therefore, only clean water will flow into the cistern. When the down fall of water ceases, 15 the water which has accumulated in the float chamber will seep therefrom through the vent 14, and it is to be noted that this vent is very small so that the leakage of water 20 will be exceedingly slow and the liability of the float descending and returning the valve to the position shown in full lines in Fig. 2 before the cistern is filled will be practically eliminated. As the water leaks from the 25 float chamber, the float, of course, will descend and eventually will return the cut-off to its initial position so that, when the rain again falls, the flow initially will be through the outlet 2 and dirt which may be washed 30 from the roof will be prevented from passing into the cistern. The device is exceedingly simple in the construction and arrangement of its parts and will operate efficiently and automatically, the construction 35 being such that the device is not apt to get

out of order and the necessity for repairs will be minimized.

Having thus described the invention, I claim:

1. A device for the purpose set forth comprising a casing having a plurality of outlets in its bottom, a float chamber between the outlets, a tilttable cut-off plate mounted within the casing above and extending entirely across the float chamber and having a central opening, there being a vent in the bottom of the float chamber, and an imperforate float in the float chamber connected with one side of the tilttable valve whereby to normally direct water into one outlet. 45

2. A device for the purpose set forth comprising a casing, a plurality of outlets in the bottom of the casing, a float chamber between the outlets, deflectors extending downwardly and inwardly within the casing from the ends thereof at the top thereof, a tilttable cut-off plate mounted in the casing above and extending entirely across the float chamber and adapted to engage at its ends with either deflector and within the outlet 60 at the respectively opposite side of the casing, an imperforate float within the float chamber, and a connection between the float and one end of the valve, the cut-off plate having a central opening therethrough to permit some water to drain into the float chamber and the float chamber having a vent in its bottom. 65

In testimony whereof I affix my signature.
JAMES P. OLSON. [L. S.]
